BASKET STRUCTURE

Catherine Pultar, Union, N. J.

Application September 21, 1936, Serial No. 101,728

4 Claims. (Cl. 41—10)

This invention relates, generally, to wire baskets and the invention has reference, more particularly, to a novel beaded wire basket and to the method of making the same.

5 The principal object of the present invention is to provide a novel beaded wire basket that may be readily made by children or others by merely following a few simple instructions.

Another object of the present invention lies 10 in the provision of a simple method by which the novel basket of this invention may be made, the said method being such as to train children to become skilled in the use of their hands.

Still another object of the present invention is 15 to provide a novel beaded wire basket that is adapted for a wide variety of uses, and is exceedingly attractive in appearance, the said basket being rugged and having a long life in use.

Other objects of this invention, not at this time 20 more particularly enumerated, will be clearly understood from the following detailed description of the same.

The invention is clearly illustrated in the accompanying drawing, in which:

25 Fig. 1 is a perspective view of the novel basket of this invention, and

Figs. 2 to 5 are views illustrating steps in the making of the basket of Fig. 1.

Similar characters of reference are employed 30 in said views, to indicate corresponding parts.

Referring now to the several figures of the drawing, the reference numeral 1 designates the novel basket as a whole, the said basket consisting of a bottom portion 2, flaring sides 3 and 35 a handle 4, all of which parts are made of beaded wire and have the appearance of lattice-work.

In making up the basket 1, the bottom portion 2 is first made by taking a piece of wire 5, which may be about 9 inches long, for example, 40 and stringing beads 6 on this wire for about 5 inches of its length. The end portion of the beaded wire containing about 12 beads is now

bent into a square or circular loop 6' and the free end of the wire bent preferably at least twice 45 tightly around the main stem of the wire as shown at 7. A portion of the main stem of the wire adjoining joint 7 and containing about 8 beads is now bent into a half circle or loop 8, the end of the half circle being attached to the 50 square 6' at the point 9 thereof by twisting the main stem at least twice around the wire of loop 6'.

Three more half circles 8 are now formed in succession and attached at points 9', 9'' and 7 to the loop 6' by twisting the main stem around 55 the wire of loop 6', thereby forming the structure

shown in Fig. 3 constituting a part of the basket bottom.

To complete the basket bottom, a beaded wire about 8 inches long is used, and one end of the same attached to the center of one of the half 5 circles 8 by twisting an end of the beaded wire about the central point 10, thereby forming the joint 11. A portion of the beaded wire containing 10 beads is now bent into a crescent shaped loop 10 and attached to the center of the next half circle 8, i. e. at the part 10 thereof, the attachment being accomplished as before by twisting the main stem of the wire twice about the point 10, thereby forming a segment 12 constituting a portion 15 of the bottom periphery. Three more segments 12 are now made in succession, thereby completing the basket bottom as shown in Fig. 4.

In forming the sides of the basket 1, a beaded wire about 16 inches long has one end thereof attached by twisting the same upon the center of 20 one of the segments 12, i. e. at a point 13 of the segment. A portion of the wire containing 8 beads is then bent into substantially a half circle 14 and attached to the segment 12 at the next point 13 spaced four beads away. Then another 25 half circle 14 containing 8 beads is formed and attached to the next point 13 (see Fig. 4) until the first side row of lattice-work is formed.

In forming the second row of lattice-work, another beaded wire about 16 inches long has one 30 end thereof attached by twisting to the top center of one of the half circles 14. A portion of the wire containing 8 beads is then bent into substantially a half circle 15 and attached by twisting the main stem of the wire twice about the 35 top center of the next half circle 14 and this is continued until the second row of lattice-work is complete. The third and top row of lattice-work is similarly formed, thereby completing the sides of the basket. If desired, the basket sides 40 may have additional or even fewer rows of lattice-work.

The handle 4 is formed by taking two pieces of beaded wire of the same lengths, for example, 10 inches long and twisting the same together at 45 intervals at the points 16, there being, for example, 8 beads on each wire between consecutive points 16. The ends of the wires are twisted about the top centers of half circle loops 17 of the top row of lattice-work forming the basket 50 sides, thereby completing the basket.

Although a basket of definite size and number of beads used has been described to aid in the understanding of the invention, yet it will of course be understood, that the basket may be 55

made of any size desired and that the number of beads used may also be varied as desired. The completed basket has a very attractive appearance and is useful for a variety of purposes, the making of the basket being interesting and instructive, especially to children.

As many changes could be made in the above construction and many apparently widely different embodiments of this invention could be made without departing from the scope thereof, as defined by the following claims, it is intended that all matter contained in the above description or shown in the accompanying drawing shall be interpreted as illustrative and not in a limiting sense.

15 I claim:—

1. A basket structure comprising, strands of bendable wire having decorative beads strung thereon so as to be carried thereby, said wire strands being formed into interconnected loop formations, the connections between adjacent loop formations being formed by twisting one portion of a strand around an adjacent portion at points of intersection between said loop formations.

20 2. A basket structure as defined in claim 1, wherein said loop formations are related one to

another in successive rows to form a desired con-formation of the ultimate basket structure.

3. In a basket structure, a bottom formed of a pair of strands of bendable wire having decorative beads strung thereon, one of said strands being formed into a central loop with four additional loops disposed symmetrically around said central loop and interconnected therewith at equally spaced points, and the other of said strands being formed into four segment like loops disposed symmetrically around said four loops and interconnected with the central points of the latter, the connections between said several loops being formed by twisting a strand about a previously formed loop.

4. A basket structure as defined in claim 3, having sides formed of three rows of lattice-work, each of said rows consisting of a single beaded wire strand formed into a series of loops, the loops of one row being interconnected with those of an adjacent row, and the loops of the lower row being interconnected with the segment like loops of said bottom, and a handle consisting of a row of loops formed by twisting two beaded wire strands together at regularly occur- 25 ring mutually spaced points.

CATHERINE PULTAR.
